UNITED STATES PATENT OFFICE.

WILLIAM L. LENGEL, OF READING, PENNSYLVANIA, ASSIGNEE TO THE NOLDE & HORST CO., OF READING, PENNSYLVANIA, A CORPORATION OF PENNSYLVANIA.

DROP-STITCH MECHANISM FOR KNITTING MACHINES.

Application filed November 3, 1921. Serial No. 512,482.

To all whom it may concern:

Be it known that I, WILLIAM L. LENGEL, a citizen of the United States, residing at Reading, in the county of Berks and State of Pennsylvania, have invented certain new and useful Improvements in Drop-Stitch Mechanism for Knitting Machines, of which the following is a specification.

My invention relates to circular knitting machines employing a complete circular series of needles, and my object is to produce drop-stitch patterns in the knitted fabric by the lowering out of action of certain needles arranged in spaced pairs around the needle cylinder, and to close said patterns by raising into action certain of said pairs independently of the other pairs, and subsequently raising the latter to produce a solid-knit circular fabric when desired; a further object being to positively insure the resumption of knitting by the raised needles by lifting into action first one and then the other of each of spaced pair in successive rotations of the needle cylinder. My invention is fully described in connection with the accompanying drawings showing my improved needle-actuating means and the automatic mechanism for operating the same during continuous knitting; the novel features being fully set forth in the subjoined claims.

Fig. 1 is a front elevation of a portion of a knitting machine embodying my invention, only such parts essential to the disclosure of my improvements being indicated.

Fig. 2 is a plan view of the cam ring and its cooperating parts.

Fig. 3 is a sectional view of the latter on the line 3-3 of Fig. 2; and Fig. 4 is a fragmentary section on the line 4-4 of Fig. 2.

Figs. 5, 6, and 7 are detail diagrammatic views showing successive positions of the lifter cam actuating mechanism.

Fig. 8 is an interior diagrammatic view of the developed cam ring.

Fig. 9 indicates a continuous stocking fabric product of my improved machine.

Figs. 10 and 11 indicate the pairs of needles employed among the usual short-butt and long-butt needles respectively and adapted to be lowered out of knitting action to produce drop-stitch patterns.

Fig. 12 indicates diagrammatically the arrangement of the specially-butted needles in the needle cylinder, to produce drop-

stitch patterns, and Fig. 13 shows a fragmentary view of the grooved needle cylinder and indicates the specially-butted needles only in position therein.

The machine illustrated in the drawings is similar in a general way to the type shown in Robinson's Patents No. 1,262,568, dated April 9, 1918, and No. 1,339,715 dated May 11, 1920; essential improvements providing for employing a full set of needles, instead of having some removed as in the patent; and to improved means for actuating the full set of needles to produce desired drop-stitch patterns, or to close some or all of said patterns by the improved manner of lifting the needles back to action to insure their positive resumption of knitting. The advantage of having a full set of needles in knitting a stocking not only permits of closing any drop stitch pattern when desired, but permits of knitting a plain-fabric advance-toe portion, see Fig. 9, which plain fabric greatly facilitates the transfer of the stocking to a looper machine for the usual finishing operation.

In my improved machine I employ, as usual, a needle cylinder having approximately two half-circle series of needles provided respectively with long butts and short butts, the former adapted to knit the front half and top foot portion of a stocking, and the latter the rear half and bottom of the foot and the heel and toe pockets, all in well known manner.

To produce drop-stitch patterns, I preferably employ, in spaced pairs arranged around the needle cylinder, as indicated in Figs. 12 and 13, needles having special butts, which I substitute for the usual long and short butt needles at these places; those employed among the regular short butt series comprising pairs made up of a needle 10 having an intermediate length butt 10^a, and a needle 11 having an intermediate length butt 11^a with a bottom extension 11^c, as shown clearly in Fig. 10; and those employed among the regular long butt series comprising pairs made up of needle 12 having an intermediate length butt 12^a with an additional butt 12^b spaced above the latter, and a needle 13 having an intermediate butt 13^a and an additional butt 13^b similar to needle 12, with a bottom extension 13^c similar to the extension of needle 11, which needles 12 and 13 are clearly indicated in

Fig. 11. The intermediate length butts 10^a, 11^a, 12^a, and 13^a, as the name implies, are of a length intermediate the length of the regular long and short butts, while the additional butts 12^b and 13^b are of a length shorter than the regular short butts, and are arranged to clear the slightly cut-back inner wall of the cam cylinder and its operating cams except such of the latter as are intended to operate on these additional butts.

Referring now to Fig. 8, which shows only cams essential to disclosing my invention, 20 represents the top center cam, 21 and 22 the stitch cams, 23 the center levelling cam, and 24 the needle rest, all of which are as heretofore and operate in well known manner upon the needle butts. Beneath the needle rest 24 and parallel therewith, is an idle butt-path 25 for the lowered needles, which path communicates with the needle rest through inclined outlet passage-ways 26 and 27 and inlet passage-way 28; a medium-butt down-cam 30 being movable into the path of the needle butts at the entrance to the latter passage-way, and lifter cams 31 and 32 controlling the return movements through passage-ways 26 and 27 as hereinafter more fully described. 40—40^a represents a two-part instep-cam, sometimes heretofore called a dividing-cam, the raising portion 40 thereof being cut back so as to act only on the long butts, while the lowering portion 40^a acts on both long and intermediate butts. 41 and 42 indicate respectively an extra-butt lifting cam, and an extra-butt lowering-cam, the former being moved into and out of operative position only when the instep-cam is in raised position, and the latter being moved into position only when medium-butt down-cam 30 is swung out of position. The particular mechanism for automatically operating these needle-actuating cams will later herein be more fully described, but first I will now describe the required cam movements to produce a stocking having a drop-stitch pattern as indicated in Fig. 9, which shows a continuous stocking fabric that is afterwards severed as usual into separate lengths on the line 9—9. At this point of severance a plain knit tubular fabric is being produced by the action of all the needles, which plain fabric is changed at the beginning of the next stocking leg by the lowering out of action of the spaced pairs of needles 10—11 and 12—13 to produce drop-stitch patterns around both the front and rear, which lowering is accomplished by moving into action medium-butt down-cam 30. This cam 30 acts not only upon the intermediate butts but also upon all long butts, the latter however being raised back to the knitting path by the inclined wall 29 at the entrance to passage-way 28, which passage-way is of a depth to

receive only the intermediate-butts and lower them to idle path 25.

The needles 10—11 and 12—13 are thus lowered out of knitting action with their intermediate butts lying in idle path 25, in which position they are continued during the knitting of the entire leg portion of the stocking, producing the desired drop-stitch patterns. At the beginning of the heel pocket it is desirable, as is well understood, to close the rear drop stitch patterns so as to knit a plain fabric in the heel, foot and toe, for greater strength and comfort, and in order to positively assure the resumption of knitting by the returned needles I provide improved means for lifting first one of each pair of lowered needles,—all needles 11,—back to action, and in a subsequent rotation of the needle cylinder lifting the remaining needles of these pairs,—all needles 10,—back to action. It will also be understood that to continue the drop-stitch patterns unbroken down the top of the foot, needles 10 and 11 must be lifted, while needles 12 and 13 remain in non-knitting position. This lifting of the needles 10 and 11 is accomplished by lifter cams 31 and 32, the former first acting on the needle butt extensions 11^c to raise the needles 11 until their butts 11^a enter passage-way 26 which raises them back to the knitting path; after which lifter cam 32 acts upon the butts 10^a of needles 10 to return them through passage-way 27 back to knitting action. Lifter cams 31 and 32 will of course act also upon extensions 13^c and 12^c of needles 13 and 12 respectively, but these needles are lowered before passing the knitting cams by moving into action extra-butt down-cam 42, which acts upon extra butts 13^b and 12^b to lower their needles until their butts 13^a and 12^a enter passage-way 28 and back to the idle path 25. Upon the withdrawal of lifter cams 31 and 32 and extra-butt down-cam 42, needles 10 and 11 are back in knitting action among the short butt needles and needles 12 and 13 are still lowered out of action in idle path 25, which action has been accomplished in a simple manner requiring a minimum number of needle butts and extra cam 42. Instep cam 40—40^a is then operated as heretofore to raise the long butt needles for the usual reciprocative knitting of the heel pocket, and again operated at the end of the latter to return these long butt needles for the knitting of the foot portion. Before beginning the toe pocket I prefer first to close the drop stitch patterns which have been continued down the top of the foot, and to this end I again operate cams 31 and 32 to lift first all needles 13 and then all needles 12 in the manner heretofore described, cam 42 remaining idle at this time so that the needles 12 and 13 will be returned to knitting action to produce from this point a plain knit

tubular fabric. In operating instep-cam 40—40^a for lifting the long butt needles preparatory to reciprocatively knitting the toe pocket, it will be understood that the needles 12 and 13 must at this point also be raised with the latter, and to accomplish this I employ extra-butt lifting-cam 41 with cam 40—40^a which acts upon extra butts 12^b and 13^b to raise them as portion 40 raises the long butts, all being lowered together later after completion of the heel pocket by the portion 40^a. The plain knit tubular fabric is continued beyond the toe pocket to form an advance toe portion, this plain knit fabric greatly facilitating the transfer to a looper machine for a finishing operation.

Having thus described the sequence and essential operations of the cams to produce a knitted stocking with the desired drop-stitch patterns, I will now describe the preferred mechanism illustrated in the drawings for automatically accomplishing these cam movements.

The knitting cams 20, 21, 22, and 23 actuate the needle butts in well known manner and need no description. Instep-cam 40—40^a, as heretofore, lies always in the path of the needle butts, with portion 40 cut back so as to clear all but the long butts, and its vertical slide member 50 is raised and lowered in well known manner through bell-crank 51, pivoted at 52, said crank being connected in usual manner, not shown, with pattern drum 55 mounted on pattern drum shaft 56. Secured to the slide-way 50 is a bracket 57 to which is pivotally secured at 58, one end of a swinging arm 59, the other end of the latter extending through a vertical slot 60 in a slide-member guide-plate extension 61, and carrying an inclined-face presser-head 62. This presser-head 62 is adapted to bear against the spring-retracted shank-portion 63 of extra-butt lifting-cam 41 to move the same into needle-butt contacting position when the slide 50 is lifted. The arm 59 is free to swing on its pivot 58 but is normally held in fixed position in a horizontal plane by a spring-pressed latch member 64 pivoted to the guide plate at 65 and having an extension 66 extendable under the arm 59 to support the latter, and another releasing extension 67 adapted to contact with a projection 68 carried by the rotatable needle cylinder, which contact swings the latch to free the arm 59. It will be seen that when the cam 40—40^a is moved to raised position by vertical lifting of slide 50, cam 41 is projected into the path of the extra butts of needles 12 and 13 by head 62 bearing on shank 63. This action is timed so that portion 40^a is elevated out of the way before cam 41 is projected, and projection 68 releases the latch member 66 so as to permit said spring-retracted cam 41 to withdraw before slide 50 is operated to lower

cam 40—40^a, avoiding any clashing of the cams in the necessarily restricted space in which they must act.

Extra-butt down-cam 42, adapted as heretofore described, to lower needles 12 and 13 until their intermediate butts 12^a and 13^a pass through passage-way 28 back to idle path 25, is provided as shown with a spring retracted shank portion 70, the projecting end 71 thereof being preferably bent to form an angular extension against which a presser arm 72, carried by vertical sleeve shaft 73 is adapted to press cam 42 into the path of the needle butts. Intermittent partial rotary movement is imparted to said sleeve shaft 73, as shown, by contact of its actuating arm 74 with a pattern lug 75 on pattern drum 55.

Medium-butt down-cam 30 is carried by an arm 80 pivoted at 81 so as to swing said cam in a vertical plane from and toward the needle butt path, a spring 82 normally maintaining the cam in idle raised position. The arm 80 has a divided vertical extension, one portion 83 forming a contact projection for a purpose later herein described, and the other extension 84 adapted for contact of a presser arm 85, the space between forming a recess for a spring locking latch 86. The presser arm 85 is carried by a vertical shaft 87 and is adapted to swing the cam 30 in a preliminary movement preparatory to entering the same into the path of the needle butts, partial rotary movement being imparted to shaft 87 by its actuating arm 88 contacting with a pattern lug 89 on the pattern drum 55. The movement of the presser arm 85, as stated, only performs a preliminary swinging movement of the cam 30 toward the path of the needle butts, the final movement of the latter being accomplished by the needle-cylinder-carried projection 68 bearing on extension 83 to depress the latter and swing the cam 30 through its final movement into the path of the needle butts, in which position it is now held by latch 86 entering the opening between extension 83 and 84. The projection 68 is properly set between the drop stitch patterns so as to enter the cam 30 at the proper point between said patterns insuring very accurate operation and permitting close location of the patterns. Upon releasing latch 86 the cam 30 will be immediately withdrawn by its spring 82, the latch releasing movement being accomplished through its stud 90 and a releasing finger 92 carried by said presser arm 85. The withdrawal movement of arm 85 from projection 83 is caused by the pattern drum 55 turning to free shaft-actuating arm 88 from its pattern lug 89, such movement of arm 85 swinging the releasing finger thereon to contact with stud 90 of the latch and free the latter.

This preliminary setting of cam 30 by the pattern mechanism, and completion of its movement by cylinder-carried cam 68 is to insure the snapping into position of said cam between the closely arranged drop stitch needles. Referring to Fig. 12 it will be seen that the timing of this entry of cam 30 between the pairs of drop stitch needles 10-11 must be very accurate, and any slight variation in the pattern mechanism, as a stretching of the pattern chain, controlling drum 55 would be greatly increased at the point of action on arm 84 of cam 30, causing said cam to strike the extended butts of needles 10-11 instead of swinging to lowered position between spaced pairs of the same. By preliminarily setting cam 30 leaving only a slight further movement for action of cam 68, such entry between the pairs of needles 10-11 is insured, as cam 68, carried with the needle cylinder, may be accurately positioned, and the pattern-mechanism may be set to act more or less ahead of time. This same nicety of adjustment is required in shifting cams 31 and 32 into action, and is provided for by cylinder carried trips 130 and 131 which will properly shift said previously set cams at a very definite point in the rotation of the needle cylinder, as will now be more fully described.

Lifter cams 31 and 32 as stated, control the outlet passageways 26 and 27 respectively and operate in successive rotations of the needle cylinder to raise the needles of each drop stitch pair singly so as to positively insure their resumption of knitting; and their automatic operation from the pattern drum, as shown in the drawings, is preferably provided for as follows:

Two movements of these cams 31 and 32 are required in the knitting of a stocking, one for lifting needles 10 and 11 before the forming of the heel pocket, and another for lifting needles 12 and 13 before forming the toe pocket; the pattern drum 55 accordingly having two pattern lugs 100 and 101, identical in shape and spaced so as to perform the movements at the proper time. The lugs 100 and 101 have two steps, as shown, contacting with one end of a centrally pivoted lever 102 and imparting thereto two progressive lifting actions, timed to occur in different rotations of the needle cylinder. The opposite end of lever 102 is connected by a link 103 to one end of a second lever 104, pivoted at 105 and having its opposite end 106 inturned and forked as shown to engage a rocker arm 107. Cam 31 is vertically movable in the cam ring as shown, with an integral stud 108 projecting outwardly through a slot 109 in said ring wall, and carrying a pendant arm 110. A stud 111 on the free end of arm 110 is engaged in an angular slot 112 of a plate 113 pivoted at

114 and provided with a stud 115 engageable by the end 116 of rocker arm 107. A coil spring 117 on the pivot post 118 for arm 107, bears on stud 115 to swing the plate 113 on its pivot 114. Cam 32 is also vertically movable in the cam ring, with a ring-slot-engaged projecting stud 120 carrying a pendant arm 121, the latter provided with a stud 122 engaged in an angular slot 123 of a plate 124 pivoted at 125. Also pivoted at 125 is an arm 126 carrying a stud 127 engageable between the opposite spread forked end 128 of rocker arm 107; a coil spring on pivot shaft 125 connecting said plate 124 and arm 126 normally tends to swing them toward one another. The cooperation of the parts above set forth to produce the desired action of cams 31 and 32, will now be described, reference being had particularly to Figs. 5, 6, and 7, in which Fig. 5 shows the position assumed by the cooperative parts when cams 31 and 32 are in idle lowered position; Fig. 6 the position of the parts after a preliminary movement before the actual movement of cam 31, and Fig. 7 a similar preliminary movement of the parts for cam 32, and the locked position of the parts for cam 31 after its final movement.

Fig. 5, as stated, shows the parts in the position assumed when cams 31 and 32 are in idle lowered position. Before dividing the needles for the reciprocative knitting of the heel pocket, pattern drum 55 moves its lug 100 until the end of lever 102 is lifted upon the first step of said lug, this movement swinging arm 107, through connecting link 103 and lever 104, to the position shown in Fig. 6. In the latter position the end 116 of arm 107 has moved away from lug 115, permitting spring 117 to swing plate 113 on its pivot 114 until pendant arm 110 is swung to vertical position against a stop, not shown, lug 111 engaging in the vertical portion of angular slot 112 to limit the swing of said plate. At this point a trip 130 carried by the needle cylinder passes under pendant arm 110 to raise the same and its connected cam 31 and lift the latter into active position in the cam ring, in which position it is locked by further swinging movement of the plate 113 permitted by the lifting of stud 111 to the angular portion of slot 112 and the clearance provided between the stud 115 and end 116 of arm 107, this final swinging movement of the plate being indicated in Fig. 7. When pattern drum 55 further rotates in a subsequent rotation of the needle cylinder, lever 102 is lifted upon the second step of lug 100 and arm 107 is further swung to the position indicated in Fig. 7. In this latter position arm 126, through engagement of stud 127 in forked end 128 of rocker arm 107, is swung on its pivot 125, swinging also its spring connected plate 124 until pendant

arm 121 comes to rest in a vertical position against a stop, not shown, with its lower end in position to be acted upon by a second trip 131 on the needle cylinder which latter lifts said arm and its connected cam 32 to raised operative position, and it is held locked in this position by spring-pressed plate 124 swinging to the position shown in dotted lines to engage the stud 122 in the angular portion of slot 123. This further movement of rocker arm 107 had no further effect on cam 31 or its operating parts as spring 117 resting on stud 115 merely gave without action as plate 113 was in locked position against arm 110, and the latter was bearing against a limiting stop to prevent its further swinging movement. After lever 102 rides over lug 100, spring 133 acts thereon to return rocker arm 107 to the position shown in Fig. 5, restoring the cam operating parts to the position therein shown, ready for a similar operation again when lug 101 acts upon lever 102.

The above preferred means for operating the several cams of the needle cylinder to perform the sequence of required movements heretofore specifically described to produce a desired drop-stitch pattern stocking with the improved manner of raising the needles of the pairs in the two half-circle series are all automatically effected from the pattern drum; which latter however only preliminarily sets the two lifter-cams and the medium-but down-cam, the completion of their operative movements being determined by cylinder-carried means so that their entry between the patterns may be accurately timed. The particular mechanism described may of course be modified without departing from my invention, and the pattern stripes may be varied as desired, and owing to the needle cylinder having a full set of needles, plain knit fabric may be produced at will.

What I claim is:

- 45 1. In a circular knitting machine, a needle cylinder provided with certain specially-butted needles, and needle operating mechanism comprising needle lowering means effective operative upon said specially-butted needles only, pattern-controlled means for preliminarily setting said lowering means, and cylinder-carried means for completing the operative movement of said lowering means.
- 55 2. In a circular knitting machine, a needle cylinder provided with certain specially-butted needles, and needle operating mechanism comprising needle raising means effectively operative upon said specially-butted needles only, pattern controlled mechanism for preliminarily setting said raising means, and cylinder-carried means for completing the operative movement of said raising means.
- 65 3. In a circular knitting machine, a needle

cylinder provided with certain specially-butted needles, and needle operating mechanism comprising needle lowering and needle raising means effectively operative upon said specially-butted needles only, pattern-controlled means for preliminarily setting said lowering and raising means, and cylinder-carried means for completing the respective operative movements of said lowering and raising means.

4. In a circular knitting machine, a needle cylinder provided with a pair of needles having different butts and adapted to be lowered out of the knitting path to form drop-stitch patterns, and needle operating mechanism comprising means acting upon the butt of one needle of said pair to raise it into the knitting path, means acting upon the butt of the other needle of said pair to raise it into the knitting path, pattern-controlled means for preliminarily setting said butt-actuating means in successive rotations of the needle cylinder, and cylinder-carried means for completing the respective operative movements of said butt-actuating means.

5. In a circular knitting machine, a needle cylinder provided with a pair of needles having different butts, and needle operating mechanism comprising means acting upon the butt of one needle of said pair to raise it into the knitting path, means acting upon the butt of the other needle of said pair to raise it into the knitting path, and means acting upon the butts of both needles to jointly lower said pair out of knitting action to form a drop-stitch pattern, pattern-controlled means for preliminarily setting the respective butt-actuating means in different rotations of the needle cylinder, and cylinder-carried means for completing the operative movement of each butt-actuating means.

6. In a circular knitting machine comprising two approximately half-circle series of needles having long-butts and short-butts respectively; a pair of needles in each of said half-circle series having intermediate butts and one needle of said pairs having a bottom butt extension and both the needles in the pair in one series having an extra-but; and needle operating mechanism comprising cams operable upon said needle butts at determined intervals to lower the needles in both said series out of knitting action to form drop-stitch patterns, pattern-controlled means for preliminarily setting said cams, and cylinder-carried means for completing the operative movements of said cams.

7. In a circular knitting machine comprising two approximately half-circle series of needles having long-butts and short-butts respectively; a pair of needles in each of said half-circle series having intermediate

- butts and one needle of said pairs having a bottom butt extension and both the needles of the pair in one series having an extra-butts; and needle operating mechanism comprising cams operable upon said needle butts at determined intervals to raise into the knitting path in one rotation of the knitting cylinder the bottom-butt-extension needle of the pair in one of said series and in a succeeding rotation to raise the remaining needle of the pair in said series, pattern controlled means for preliminarily setting said cams and cylinder-carried means for completing the cam movements.
15. 8. In a circular knitting machine comprising two approximately half-circle series of needles having long-butts and short-butts respectively; a pair of needles in each of said half-circle series having intermediate butts and one needle of said pairs having a bottom butt extension and both the needles of the pair in one series having an extra-butts; and needle operating mechanism adapted to raise into the knitting path the pair of needles in one half-circle series comprising cams operable upon said needle butts at determined intervals to raise into the knitting path in one rotation of the needle cylinder the needles having a bottom-butt extension, and in a succeeding rotation to raise the remaining needles, and to re-lower out of said path the needles having an extra-butts before action thereon by the knitting cams, pattern-controlled means for preliminarily setting said cams, and cylinder-carried means for completing the cam movements.
30. 9. In a circular knitting machine comprising two approximately half-circle series of needles having long-butts and short butts respectively; a pair of needles in each of said half-circle series having intermediate butts and one needle of said pairs having a bottom butt extension and both the needles of the pair in one series having an extra-butts; and needle operating mechanism adapted to raise into the knitting path the pair of needles in one half-circle series comprising cams operable upon said needle butts at determined intervals to raise into the knitting path in one rotation of the needle cylinder the needles having a bottom-butt extension, and in a succeeding rotation to raise the remaining needles, and to re-lower out of said path the needles having an extra-butts before action thereon by the knitting cams, pattern-controlled means for preliminarily setting each lifter cam, and cylinder-carried trip-cams acting respectively on said preliminarily set lifter cams to complete their operative movements.
10. In a circular knitting machine comprising two approximately half-circle series of needles having long-butts and short butts respectively; a needle in each half-circle series having an intermediate butt and said needle in the long-butt series having an extra-butts; and needle operating mechanism comprising an instep-cam acting upon long-butt needles only to raise them preliminary to reciprocative knitting, and an extra-butts lifter cam adapted to equally raise the extra-butts needle.
25. 11. In a circular knitting machine comprising two approximately half-circle series of needles having long-butts and short-butts respectively; a needle in each half-circle series having an intermediate butt and said needle in the long-butt series having an extra-butts; and needle operating mechanism comprising an instep-cam acting upon long-butt needles only to raise them preliminary to reciprocative knitting, and an extra-butts lifter cam adapted to equally raise the extra-butts needle, pattern-controlled means for moving said extra-butts cam into the path of the needle butts after the positioning movement of said instep-cam, and cylinder-carried means for withdrawing said extra-butts cam preliminary to the withdrawal movement of said instep-cam.
- In testimony whereof I affix my signature.
WILLIAM L. LENGEL.
